CALCULATING MACHINE

Ettore Sottsass, Milan, Italy, assignor to Ing. C. Olivetti & Co., S.p.A., Ivrea, Italy, a corporation of Italy

Filed Nov. 22, 1965, Ser. No. 88,172

Term of patent 14 years

(Cl. D64—11)

Fig. 1

Fig. 2

FIG. 1 is a front perspective view of a calculating machine showing my new design;

FIG. 2 is a rear perspective view thereof.

The essential features of the design reside in the portions shown in full lines on the drawing.

I claim:

The ornamental design for a calculating machine, substantially as shown and described.
